Their Attorney

UNITED STATES PATENT OFFICE

EARL JAMES CARD AND VICTOR ADOLPH GRONBERG, OF JAMESTOWN, NEW YORK,
ASSIGNORS TO JAMESTOWN METAL EQUIPMENT CO., INC., OF JAMESTOWN, NEW
YORK, A CORPORATION OF NEW YORK

DRAWER

Application filed December 17, 1925. Serial No. 76,062.

This invention relates to an improvement in a furniture drawer, and more particularly in the drawer head and its construction.

Prior to this invention the common practice was to make blisters in the bottom or sides of the drawer body to position the inner face of the drawer head. This is very objectionable because often papers or cards in the drawer are torn by such blisters.

10 The primary object of this invention is to provide a drawer having a head which is rigidly and securely fastened in place without the use of blisters, the points of fastening being entirely concealed when the drawer 15 is completed.

Another object of this invention is to provide a drawer head comprising an outer plate, an intermediate plate and an inner plate, the intermediate plate being provided with 20 swells at certain portions to stiffen the head so that the danger of bending at the point where the handles are secured is practically eliminated.

Other objects of this invention will appear 25 from a consideration of the following specification taken in connection with the drawings which form a part thereof, and in which

30 Fig. 1 is a perspective view of a drawer having a head constructed in accordance with this invention;

Fig. 2 is an enlarged vertical cross section of the head end of the drawer;

Fig. 3 is a transverse section taken along the line 3—3 of Fig. 2, showing in addition 35 to the drawer head a plan view of the bottom of the drawer; and

Fig. 4 is a sectional view taken along the line 4—4 of Fig. 3.

Referring to the drawings, the reference 40 numeral 10 is employed to designate a drawer comprising a head 11, a bottom wall 12, side walls 13 and a rear wall 14. The particular construction of the bottom, side and rear walls forms no part of this invention, and 45 it will be understood that any desired way of assembling and uniting these portions of the drawer can be followed. In the present illustration, however, the bottom wall is provided with a central recess 15, in which is 50 mounted a channel 16, and a longitudinal rod

17 projecting through the drawer head extends through the channel 16 and terminates at rear wall 14.

The drawer head 11 comprises an outer plate 18, an intermediate plate 19 and an inner plate or cover 20. The side flanges of the outer plate 18 are bent rearwardly substantially at right angles to the front face at 21, inwardly at 22, substantially at right angles to the section 21, and rearwardly at 23 at right angles to the section 22.

The bottom edge of the outer plate is similarly provided with sections 24, 25, and 26 substantially at right angles to each other and the upper edge is bent rearwardly at 27 and downwardly at 28. Thus at the sides are formed vertical recesses 29, at the bottom is formed a horizontal recess 30 and at the top is formed a horizontal recess 31.

The intermediate plate 19 has side flanges 32 and a flange 33 across the bottom edge which is in line with the lower edge of the side flanges 32. Formed in the main portion 34 of the plate 19 are horizontal ribs or swells 35, shown particularly in Fig. 2. Secured by 70 welding or otherwise to the inner face of the intermediate plate below the swells 35 is a clip 36, which enters a slot 37 in the flange 33. The clip 36 extends below the flange 33 and the bottom edge of the plate 20, and is 75 drilled and tapped to receive the threaded shank of knob 46.

The intermediate plate 19 is rigidly secured to the outer plate 18 in any desired manner with its upper edge extending into the recess 85 31 and the clip 36 extending into the recess 30, as shown in Fig. 2. A handle 38 is secured to the plates 18 and 19 between the ribs or swells 35. Since the plates 18 and 19 are rigidly connected it is obvious that the 90 swells 35 act to stiffen the plates against the strain exerted by the handle 38, and that the flange 33 serves the same purpose. The provision of the ribs in the plate 19 only avoids the formation of any depressions in the outer 95 face of the drawer head.

The side flanges 32 of the plate 19 are parallel to and spaced from the sections 23 of the outer plate 18 a sufficient distance to permit the introduction of the ends of the side 100

walls 13 between them. The sections 23, side walls 13 and flanges 32 are then suitably connected by welding or other means, while the bottom wall 12 is similarly joined to the section 26 of the outer plate.

5 The inner plate 20 functions primarily to cover the inner faces of the outer and intermediate plates and to provide a smooth inner front surface for the drawer. Occasions 10 arise, however, when it is desirable to get at the inner faces of the plates 18 and 19, and consequently the plate 20 is made removable. The plate 20 has side walls 39, a top wall 40, and a bottom wall 41, these walls being all at 15 right angles to the face portion 42 of the plate 20. The plate 20 is of such dimensions that the side walls 39 will enter closely within the flanges 32 and rest against the inner face of the portion 34, while the body 42 of the plate 20 is in the same plane as the outer edge of 20 the flanges 32.

The flange 33 terminates short of the flanges 32 to provide spaces therebetween. The top wall 40 is bent upwardly at the portion 43 and 25 outwardly at the portion 44, to form a bead which enters and fills the recess 31 in the outer plate 19. The bottom wall 41 is provided with a longitudinal rib or depression 45 so located that it will enter the recess 30 at the 30 bottom of the outer section 19 between the front edge of the bottom 12 and the plate 18 and is notched to clear the clip 36. After the plates 18 and 19 have been rigidly secured to the drawer proper the plate 20 is installed 35 by inserting the bead formed by the portions 43, 44 into the recess 31 and then swinging the plate 20 around the edge of the section 28 as a fulcrum, until the depression 45 enters the recess 30, the walls 39 taking their position 40 against the inner face of the flanges 32.

The plate 20 is thus quickly and easily inserted and can be removed at any time should occasion arise without difficulty. This plate covers the joinder of the plates 18 and 19 with 45 the drawer proper and also covers the flange 33 and the ribs 35, so that the inner front of the drawer is absolutely smooth and will not catch the papers or other documents inserted in the drawer.

50 The knob 46 of the rod 17 is externally threaded and the aperture in the clip 36 through which the pin passes is internally tapped to receive the threaded portion of the head 46 and thus fix the rod in position. The apertures 47 and 48 in the outer plate 18 and 55 in section 25 for the rod 17 are larger than the pin so that it passes through them freely.

While one embodiment of this invention 60 has been shown and described, applicants are not limited thereto, since it is obvious that other embodiments can be made without departing from the spirit and scope of this invention, as set forth in the following claims.

65 Having thus set forth our invention, what

we claim as new and for which we desire protection by Letters Patent is:

1. In a drawer, a head comprising an outer plate, an intermediate plate and an inner plate, the edges of said outer plate being 70 formed to provide recesses, the side and bottom edges terminating in rearwardly extending flanges behind said recesses, the side edges of said intermediate plate terminating in rearwardly extending flanges, a clip rigidly secured to the lower portion of said intermediate plate, means for securing said intermediate plate to said outer plate with the upper edge of said intermediate plate extending into the recess at the upper edge of said outer plate, said clip extending into the recess at the lower edge of said outer plate, and the flanges of said intermediate plate parallel to and separated from the side flanges of 75 said outer plate to form spaces which the front ends of the side walls of the drawer proper enter when said head is applied thereto, the bottom wall of said drawer being in surface contact with the bottom flange of said outer plate, said inner plate having outwardly extending side flanges which when said inner plate is assembled with said outer and intermediate plates after the drawer proper is secured, rest against the inner faces of the side flanges of said intermediate plate. 80

90 2. In a drawer, a head comprising an outer plate, an intermediate plate and an inner plate, the top and bottom edges of said outer plate being formed to provide horizontal recesses, a strip adapted to form a clip rigidly secured to the lower portion of said intermediate plate and means for securing said intermediate plate to said outer plate with the upper edge of said intermediate plate extending into the upper horizontal recess of said outer plate and said clip extending into the lower horizontal recess of said outer plate. 95

100 3. In a drawer, a head comprising outer, intermediate, and inner plates, rearwardly turned flanges terminating the vertical edges 110 of said outer and intermediate plates, drawer side walls engaged with said head between adjacent flanges of said outer and intermediate plates, flanges terminating the top and bottom of said outer plate providing horizontal recesses, a clip-like strip secured to the lower portion of said intermediate plate and means securing said intermediate plate to said outer plate with the upper edge of 115 said intermediate plate extending into the upper horizontal recess of said outer plate and said strip extending into the lower horizontal recess of said outer plate. 120

125 4. In a drawer, a head comprising outer, intermediate, and inner plates, horizontal ribs extending across said intermediate plate, rearwardly turned flanges terminating the vertical edges of said outer and intermediate plates, drawer side walls engaged with said head between adjacent flanges of said outer 130

and intermediate plates, flanges terminating the top and bottom of said outer plate forming horizontal recesses, a clip-like strip secured to the lower portion of said intermediate plate and abutting the lowermost of said horizontal ribs, means securing said intermediate plate to said outer plate with the upper edge of said intermediate plate extending into the upper horizontal recess of said outer plate and said strip extending into the lower horizontal recess of said outer plate, and a handle secured on the face of said outer plate, said handle being secured to said intermediate plate between said horizontal ribs whereby to strengthen said outer and intermediate plates against distortion caused when said drawer is moved inwardly and outwardly by means of said handle.

In testimony whereof we have affixed our signatures.

EARL JAMES CARD.
VICTOR ADOLPH GRONBERG.
